(57) **CLAIM**

The ornamental design for a portable building, as shown and described.

DESCRIPTION

FIG. 1 is a first perspective view of the portable building in my new design;

FIG. 2 is a second perspective view of the portable building with a front porch thereof;

FIG. 3 is a rear view of the portable building with windows thereof;

FIG. 4 is a front side view of the portable building with a front door thereof;

FIG. 5 is a left side view of the portable building with light lamps;

FIG. 6 is a right view of the portable building thereof; and,

FIG. 7 is a top view of the portable building thereof. The broken lines depict portions of the portable building that form no part of the claimed design.
